UNITED STATES PATENT OFFICE.

JOHN WILSON BROWN, JR., OF PHILADELPHIA, PENNSYLVANIA, ASSIGNOR
TO THE ENTERPRISE MANUFACTURING COMPANY OF PENNSYLVANIA,
OF SAME PLACE.

DESIGN FOR A FRAME OR CASING FOR MEAT-CHOPPERS.

SPECIFICATION forming part of Design No. 24,681, dated September 17, 1895.

Application filed May 3, 1895. Serial No. 548,059. Term of patent 14 years.

To all whom it may concern:

Be it known that I, JOHN WILSON BROWN, Jr., a citizen of the United States, residing in Philadelphia, Pennsylvania, have invented
5 a certain new and useful Design for a Frame for Meat-Choppers, of which the following is a specification.

My design for the casing of a meat-chopper is clearly shown in the accompanying drawings, in which—

Figure 1 is a side view of the casing, and Fig. 2 is an end view of the same.

The essential feature of the design is the contour of the body, said body having at one 15 end a tapered perforated portion and at the opposite end an enlargement.

A is the body of the meat-chopper, and extending from the body at one end is a hopper

B, having a curved outline, and depending from the body A is a leg D. Extending 20 around the body A back of the hopper and leg is a band E, while the forward end a of the casing is tapered and perforated, giving the casing the appearance clearly illustrated in the drawings. 25

I claim—

The design for the casing of a meat chopper, as herein described and as shown in the accompanying drawings.

In testimony whereof I have signed my 30 name to this specification in the presence of two subscribing witnesses.

JOHN WILSON BROWN, JR.
